CLAIM

The ornamental design for a cup as shown and described.

DESCRIPTION

FIG. 1 is a front elevation view of a rotationally symmetric cup according to my new design;

FIG. 2 is a top plan view thereof; and,

FIG. 3 is a bottom plan view thereof.

The grayscale shading depicts a contrast which is part of the claimed design without claiming any particular color.

Conventional shading is illustrated for purposes of highlighting the line drawings, but forms no part of the claimed design.

The portions of the cup shown in broken lines form no part of the claimed design.
